UNITED STATES PATENT OFFICE.

EPHRAIM P. GRIGNON, OF APPLETON, WISCONSIN.

BOWLING-PIN.

1,351,421.

Specification of Letters Patent. Patented Aug. 31, 1920.

Application filed October 8, 1919. Serial No. 329,289.

To all whom it may concern:

Be it known that I, EPHRAIM P. GRIGNON, a citizen of the United States, and resident of Appleton, in the county of Outagamie, in the State of Wisconsin, have invented new and useful Improvements in Bowling-Pins, of which the following is a description, reference being had to the accompanying drawings, which are a part of this specification.

10 The present invention relates to certain new and useful improvements in bowling pins or the like and the method of constructing same.

15 The bowling pins now in general everyday use are made either from a single block of wood, or a plurality of layers or laminæ cemented together and turned to shape. Both of these forms have proven unsatisfactory, the first in that it is hard to obtain a single block of wood of a necessary size without imperfections, and further that the grain of the wood is presented to the surface at all angles and thus readily chips when subjected to severe blows.

25 The second is objectionable in that the outer layers of the laminæ are practically a thin veneer when the block is finally shaped and thus when subjected to a blow often splinters, and then further, the outermost layers of laminæ do not extend upwardly throughout the full length of the pin as will be readily understood thus considerably weakening the construction.

35 With these and other inherent objects in mind, my invention has for one of its objects to provide a bowling pin formed from a plurality of substantially V-shaped segments cemented together to form a substantially cone shaped block for shaping into the bowling pin.

40 Another object of my invention is to provide a bowling pin formed from a plurality of cemented together substantially V-shaped segments in which the grain of the wood of each segment is at substantially right angles with respect to the outer face thereof.

45 A further object of my invention is to provide a bowling pin constructed as above described which will be provided with a central core for convenience in manufacturing the bowling pin and for strengthening the same.

50 A still further object of the present invention is to provide a bowling pin of the

class described which will be of comparatively cheap construction, all things considered, and will be possessed of great strength, so that the same will withstand severe shocks without damage thereto.

55 With the above and other objects in view which will appear as the description proceeds, my invention resides in the novel construction, combination and arrangement of parts, substantially as hereinafter described, and more particularly defined by the appended claims, it being understood that such changes in the precise embodiment of the hereindisclosed invention may be made as come within the scope of the claims.

60 In the accompanying drawing I have illustrated one complete example of the physical embodiment of my invention constructed according to the best mode I have so far devised for the practical application of the principles thereof, and in which:

65 Figure 1 is a sectional view through a part of a tree or block of wood illustrating the manner of cutting the various segments employed in the manufacture of my bowling pin.

70 Fig. 2 is a bottom plan view of the assembled cone formed of a plurality of cemented together segments.

75 Fig. 3 is a side elevational view of the cone.

80 Fig. 4 is a perspective view of the dowel pin or reinforcing core for the bowling pin.

85 Fig. 5 is a top plan view of the completed bowling pin, and

90 Fig. 6 is a side elevational view of the completed bowling pin.

95 Fig. 7 is a side elevational view of another shape of block formed from a plurality of segments which I may employ.

100 Referring now more particularly to the accompanying drawing, the numeral 10 designates a bowling pin of the usual shape and formed from a plurality of segments 11 pressed and glued together and then provided with a central tapered bore 12 in which is disposed a tapered dowel pin 13 forming a core.

105 The segments 11 are cut from a tree or block of wood 14 in the form of a parallelogram, see Fig. 1, which is then diagonally bisected, as at 15, to form the segments 11. The bisecting cut or line 15 is not extended from the opposite corners of the parallelo-

gram, but is extended from a point slightly spaced from the opposite corners thereof, whereby to provide a blunt end 16 at the apex of each V-shaped segment. The grain 5 of the wood as indicated in Fig. 1 runs substantially longitudinal with respect to the parallelogram, so that when the segments 11 are formed, the grain of the wood will be substantially at right angles with 10 the outer facing 17 of the segments 11, as best shown in Fig. 2.

The segments then have their faces 18 coated with an adhesive and are then pressed into a substantially cone shaped structure, 15 see Figs. 2 and 3, and thus held together until the adhesive becomes set when the cone shaped block or blank shown in Fig. 3 will be formed. The blunt ends 16 of the segments 11 permit the positive forcing together 20 of the faces 18 of adjacent segments, in that the possibility of the inner end of one segment being longer than the other will have no effect as will be readily understood. The bore or opening thus centrally 25 formed in the cone shaped block is drilled out to form the tapered bore 12 of the completed pin and the cone shaped block is then turned down to the shape desired which is that illustrated in Fig. 6.

30 The dowel pin 13 is forced into the central bore 12 either before the cone shaped block has been turned down or afterward, and to insure the even distribution of an adhesive to the side walls of the bore 12, the opening 13 is provided with a spiral groove 20, which will carry the adhesive and distribute the same upon the side walls of the bore 12. The functions of the dowel pin or core 13 are two-fold, first in that the 35 manufacture of the bowling pin is greatly facilitated, in that slight imperfections formed in cutting the segments 11, where they are brought to a sharp point at their inner ends, would render it impossible to firmly cement the segments together, and the core 40 13 forms a bearing for each segment, thus distributing the resistance equally to all the segments, regardless of the tenacity of the adhesive.

45 50 Cutting the segments 11 from blocks of wood with the wood grain at substantially right angles to their outer faces, prevents any sharp angles between the outer circumference of the completed bowling pin and the wood grain and thus chipping of the 55 pin is practically eliminated. Furthermore, when the pin is made from a single block of wood, it is very expensive to select a block of the proper size free from imperfections whereas it is comparatively easy to 60 obtain pieces of wood of the size necessary to form the segments 11 which are free from imperfections.

From the foregoing description taken in

connection with the accompanying drawings, it is at once apparent that I provide a bowling pin which will be durable and capable of withstanding severe shocks without the splintering of the various segments forming part of the same. 65

In Fig. 7, I have illustrated a polygonal shaped block formed of segments which have been shaped by a molding machine, in which case the inner ends of the segments will have been cut so that the assembled 70 75 block will be provided with an even bore for receiving the core without the necessity of drilling or reaming.

What I claim as my invention is:

1. As an article of manufacture, a solid 80 bowling pin consisting of a plurality of substantially V-shaped segments secured together to form a unitary structure, the apex of said segments being on a straight perpendicular line.

2. As an article of manufacture, a bowling pin consisting of a plurality of segments of equal length secured together to form a unitary structure having a central bore, and a core member of a length substantially equal to the length of said segments and having a snug fit in said bore. 90

3. As an article of manufacture, a bowling pin comprising a plurality of segments cemented together to form a unitary structure having a central bore, and a core having a snug fit in said bore, said core being spirally grooved to insure the even distribution of a securing cement about the bore when the core is secured therein. 95

4. An article of manufacture, a bowling pin comprising a plurality of segments cemented together to form a unitary structure having a tapering central bore, and a tapered pin adapted to be forced in said 105 tapered bore to have a snug fit therein and provide a core for the bowling pin, said tapered pin having a groove therein whereby a cement may be distributed to the walls of the central bore when the tapered pin is 110 disposed therein.

5. As an article of manufacture, a wooden bowling pin consisting of a plurality of substantially V-shaped segments secured together to form a unitary structure, said segments each being cut from a block of wood 115 so that their grain will be at substantially right angles to their outer faces.

6. The herein described method of constructing bowling pins which consists in 120 cutting a plurality of blocks from a plank substantially parallel with the wood grain of the plank, then bisecting the blocks to form segments, then cementing the segments together, and then shaping the form thus 125 provided.

7. The herein described method of constructing bowling pins which consists in

cutting a plurality of blocks from a plank substantially parallel with the wood grain of the plank, then bisecting the blocks to form V-shaped segments, then cementing the 5 segments together to form a unitary structure, and then shaping the structure thus provided.

8. As an article of manufacture, a bowling pin consisting of a plurality of segments 10 of the full length of the pin and secured together to form a unitary structure having a round central bore, and a round core mem-

ber extending snugly into said bore substantially the full length of the segments.

9. As an article of manufacture, a bowling pin consisting of a plurality of segments 15 of the full length of the pin and secured together to form a unitary structure having a tapered central bore, and a tapered core member extending snugly into said bore 20 substantially the full length of the segments.

In testimony whereof I affix my signature.

EPHRAIM P. GRIGNON.
